UNITED STATES PATENT OFFICE.

GENEVIEVE B. WIMSATT, OF WASHINGTON, DISTRICT OF COLUMBIA.

DESIGN FOR A TEACUP.

Application filed March 23, 1928. Serial No. 25,970. Term of patent 14 years.

To all whom it may concern:

Be it known that I, GENEVIEVE B. WIMSATT, a citizen of the United States, residing at Washington, D. C., have invented a new, original, and ornamental Design for Teacups, of which the following is a specification, reference being had to the accompanying drawing, forming part thereof.

Fig. 1 is a perspective view of the teacup showing my new design;

Fig. 2 is a development of the interior of the cup;

Fig. 3 is a plan view of the bottom of the cup, looking inside; and

Fig. 4 is a development of the outside of the cup.

I claim:

The ornamental design for a teacup, as shown.

GENEVIEVE B. WIMSATT.
